BUILDING CONSTRUCTION

Robert L. Lindahl, Chicago, Ill., assignor to The Celotex Corporation, Chicago, Ill., a corporation of Delaware

Application December 16, 1939, Serial No. 309,518

3 Claims.

(CL. 20—5)

This invention relates to improvements in surfacing members adapted for ornamental surfacing and renovation, and particularly to material of this character comprising panels of insulating structural material formed from felted lignocellulose fibre, preferably bagasse fibres, which have been waterproofed and further treated for protection against insects and fungi. The panels are preferably formed rectangular in shape having the edges thereof fabricated to form a ship-lap unit or other suitable joint construction with contiguous panels and are of such a size as to simulate a length of six to eight brick and a height of from two to six courses. After being treated as above and formed into the correct size, they are suitably water-proofed and surfaced to simulate the appearance and texture of a section of masonry, particularly that formed of brick.

The use of this type of building material has proven eminently successful by reasons of its permanent decorative exterior, ease of installation, insulating characteristics, and other desirable properties. It has been found in the past, however, particularly in regions where the temperature goes below freezing, that there is a tendency for moisture to collect behind the panels, as applied for the renovation of old houses especially when applied over siding, particularly at the line of contact between the lower edge of clapboards and the rear face of these panels of simulated brick siding. Moisture collecting back of these brick siding panels is perhaps caused by the increase in humidity due to the heating system within the building with the excess moisture passing through the interior wall of the building where it condenses between the exterior face of the original building structure and the applied panels. Also, part of this moisture which gathers behind these panels is perhaps due to faulty erection in not properly caulking the joints allowing the elements to beat in; and also, where the material is affixed to the side walls by nailing, the rain, as it beats against the side of the building, tends to seep in along the nails.

Another objection in the past to this form of material is that where the brick siding panels are secured by nailing therethrough, or by the use of other securing means, there is a tendency to puncture the exterior water-proof and vapor-sealed construction of the panel allowing moisture to penetrate within the felted fibrous material which causes a weakening of the material and tendency to delamination thereof, particularly along the felting lines of the material and

also of the impregnated coating from the base material.

Another objectionable feature of this material is that since the panels are substantially long relative to the transverse dimensions of the panel there is a tendency for the panel to expand and contract along the length of the material, thus tending to open up the joints between the vertical edges of the panel and to allow moisture to penetrate to the space between the members and the surface of the building. There is also a tendency for the material at the ship-lap joints to warp, therefore detracting from the surface appearance of the finished wall.

Another condition to which members of this character have been subject is that the driving of a nail too deeply into the material, which being of felted fibrous material containing no binder or like medium to afford homogeneity and strength, causes a rupture of the surface of the board as the nail is driven through, particularly where there is no sheathing to abut against the back face of the panels. This condition generally exists particularly with the material when applied over clapboard siding due to the space formed between the clapboards and the panels. Also, another structural fault of material of this nature is that the nature of the felted fibrous material prevents the necessary mechanical bond or friction that is usually necessary in securing one material to another so that the material will not pull away from the nails. This pulling away of the material from the nail also destroys any effective seal that might be had for the nail by coating the nail head. In addition, the character of the composition board or insulating material requires close spacing of the securing means to insure solid securing of each panel to the frame or sheathing of the building.

It is, therefore, the primary object of this invention to provide a wall surfacing member wherein the aforementioned difficulties are eliminated and the prefabricated products are manufactured to minimize the possibility of failure after erection.

A further object of the invention is to provide a prefabricated unit adapted for surfacing adapted to provide a slight circulation of air between the back face of the panels and the surface to which they are erected and to further provide drainage for any amount of condensate or moisture which may collect between the contiguous faces of the panels and the surface to which they are erected and draining it to the outside.

Another object of the invention is to provide a building member of this character with preformed depressions, the impressions being intermediate the faces of the building covering member and adapted to increase the frictional resistance between the securing means and the material forming the member and also to effectively seal the interior of the member from the elements and at the same time serves to secure the vapor-sealed surfaces against failure by delamination.

Another object of the invention is to provide a building member having a base of felted fibrous material provided with preformed nail recesses and saturated throughout the intermediate portion of the material forming the bottom of the depressions with a water-proofing material and having the water-proofing material adjacent all surfaces including the walls of the depressions.

A further object is to provide a prefabricated product of this material having the strength and rigidity and the insulating properties of the material substantially unimpaired by the grooving and further treatments of the surfaces of the material.

Another object of the invention is to provide satisfactory means for securing the vertical joints and the longitudinal joints of the material to prevent warping of the edges adjacent to the joints, particularly at the ship-laps.

Another object of the invention is to provide a wall surfacing unit of this character comprising a surface saturated fibrous insulating material having preformed nail recesses with a water-proof coating nominally sealing the outer ends of said nail recesses, the intermediate portions between the face of the board at the nailing recesses saturated to increase the frictional resistance between the nail and the material.

Another object of the invention is to provide a wall surfacing unit of this description which is strong and thoroughly water-proofed and vapor-sealed, which requires fewer nails in the erection of the material and in which the frictional resistance between the material and the nails is effectively increased.

Further objects, features and advantages of the invention will become apparent from the following detailed description of the preferred embodiment and modifications thereof of the invention as claimed, and as illustrated in the accompanying drawings, where:

Figure 1 is an elevational view illustrating a preferred form of the surfacing unit and soldier course applied over clapboard siding;

Figure 2 is a rear elevational view of the preferred form of brick siding units illustrating the preferred form of back kerfing adapted for the circulation of air and drainage of condensate and moisture from between the contiguous surfaces of the prefabricated units and surface of a building, and modified forms of kerfing;

Figure 3 is an elevation in section illustrating a typical clapboard siding construction over which has been applied insulating brick siding units;

Figure 4 is a vertical sectional view illustrating the brick siding units applied directly over sheathing;

Figure 5 is an elevational view partly in section illustrating a modified form of brick siding unit applied directly to sheathing;

Figure 6 is a longitudinal sectional view along line 6-6 of Figure 2 looking in the direction of the arrows;

Figure 7 is a vertical sectional view of a brick

siding unit along line 7-7 of Figure 2 looking in the direction of the arrows illustrating the grooving of the back and impregnation of the unit from the surfaces thereof:

Figure 8 is a vertical sectional view, similar to Figure 7, of the modified construction illustrated in Figure 5;

Figure 9 is a partial sectional view taken substantially along line 9-9 of Figure 8 illustrating the unit of Figure 5 and showing the spacing of the furring strips for spacing the unit from a surface to which it is attached;

Figure 10 is an enlarged vertical sectional view along line 10-10 of Figure 1 looking in the direction of the arrows and illustrating the nailing recesses and impregnation thereof formed intermediate the faces of the building construction member;

Figure 11 is a horizontal sectional view illustrating a preferred form of clip and staple construction for affixing the vertical joints together and preventing warping thereof; and,

Figure 12 is a vertical sectional view along line 12-12 of Figure 11 looking in the direction of the arrows and illustrating the clip and staple construction.

Referring to Figure 1, the numeral 15 designates a building covering member formed from felted ligno-cellulose fibres, preferably bagasse fibres, which have been water-proofed by application of suitable sizing as by a precipitation of a rosin size thereon with alum and have also been suitably treated for protection against fungi and insects. The building covering member is preferably formed so that its height represents five courses of the usual brick wall construction and its length six bricks. It is obvious that other size panels may be fabricated but this size is very well adapted for shipping and erecting. The prefabricated brick siding units 15 are preferably formed with a ship-lap joint construction about the edges so that a continuous wall face is had when erected, providing closed joints which may be suitably sealed by caulking.

A unit 16 known as the soldier course is also formed from the same material as the unit 15 but it is preferably of such a size and design that it simulates bricks laid in mortar but standing on their ends, as contrasted with the previously described unit representing horizontal brick courses. Although the soldier course and brick siding unit have been indicated as being separately formed units, it is obvious that it is within the scope of this invention that horizontally laid courses and a soldier course may be fabricated in one unit.

In utilizing these units for surfacing a building or renovating the appearance thereof, other forms of units are used, such as corner members but these have not been illustrated as they are not necessary for the understanding of the invention. The units 15 and 16, after being cut to size and with suitable edge joint thereon, preferably are impregnated from the surfaces and edges thereof as illustrated in Figures 6, 7 and 10. This is accomplished by dipping or passing the prepared blank through a bath of saturant so that the saturant impregnates the material a slight distance from the surface to seal the material and form a water-proof sheath for the blank. The saturant is preferably molten asphalt but may be a suitable pitch or the like which will serve to seal the material and form a water-proof sheath for the blank. It is preferred that the edges of the unit shall be completely saturated for a certain

time.

distance inwardly as at 17, Figure 6, in accordance with the disclosure in the co-pending application of George E. Swenson, Serial No. 214,817, filed June 17, 1938. This saturation or impregnation causes the voids of the felted fibrous material from which the units are fabricated to become largely filled with the saturant or impregnant thus rigidifying and strengthening the edges of the unit. It is evident that the saturation of the unit at the edges, as at 17, and impregnation at the surfaces thereof, as at 18, with asphalt provides a sealed sheath for the unit formed integrally with the material from which the unit is fabricated, leaving the interior 19 thereof unimpregnated so that substantially the effective insulation value of the material is left unimpaired.

Over the outer face of the unit which is exposed to the weather there is applied by knife coating or rolling a substantial coating 20 in the form of a continuous surface layer of asphalt or like water-proof material. Colored granular material or grit 21 is applied to the coating 20 and this coating is suitably pressed by rolling or by platens to provide the depressions 22 in order to simulate masonry, brick, or other similar constructions. The soldier course in unit 16 is also formed in the same manner to simulate a brick, or masonry construction.

A unit formed as above is satisfactory except that upon erection by nailing or otherwise the securing nails or securing means which are applied to secure the siding unit in place, perforate the interior sealed portion of the unit allowing moisture to penetrate within the material causing deterioration of the material and possible delamination of the face from the material. To overcome this and to improve not only the strength of the material but to increase the frictional resistance between the material and the securing means, a preferred form of construction as illustrated in Figures 1 and 10 is utilized. Before dipping to water-proof and vapor-seal the surfaces of a unit, recesses 23 are formed in one or preferably in both sides of the material, as by drilling or pressing indentations in the material by the use of platens or by rolling. The recesses which are substantially equal in diameter at the bottom thereof to the head of the nails or other securing means used for applying the units are so formed that an intermediate portion 24 lies preferably midway between the faces of the unit. The number of these indentations is best illustrated in Figure 1 and shall be such that the units 15 and 16 may be securely affixed as they are erected in place.

The units so preformed and fabricated with the nailing recesses are then dipped and impregnated as previously described. The surface is therefore impregnated, as at 18, while the interior of the material about the nailing recesses 23 is impregnated as at 24'. The dimensions of the intermediate portion 24 formed at the nailing recesses 23 shall be such that it shall preferably be completely saturated throughout, thus completely sealing the interior of the material at this point. The saturation is possible at this point because of the fibrous character of the material as it has substantially greater porosity transverse with respect to the felting planes than at the face of the material, so that transverse saturation will extend laterally about the recesses. In addition to providing a seal for the interior of the material, it also increases the nail holding characteristics of the material, as has been disclosed and claimed in the co-pending application of

George E. Swenson, Serial No. 215,896, filed June 25, 1938.

A nail 25 or other securing means when driven through this material in applying it, as illustrated in Figure 10, has greater frictional resistance or grip, and the material about the recess is so reinforced that the nail, when subjected to normal usage, will not be pulled through the material breaking whatever seal is formed about the securing means. Nailing as defined in the claims is synonymous to securing means which includes as equivalent construction screws, and the like. The recesses 23, which are similarly formed at the back of the material, the same as at the face, also because of the impregnation about the recess prevents the breaking out of the material as the nails are driven through, particularly when the material is applied over clapboard siding.

In addition to forming an improved nailing construction for the units, the impregnated portion about the nailing recesses forms what might be called an impregnated rivet thoroughly securing the water-proofed impregnated layers 18 on opposite faces of the material together so that any delamination of these layers 18 is prevented. It is obvious that a sufficient number of these nailing recesses may be formed on the faces of the unit so that there is substantially the same effect as that of a plurality of rivets for securing the impregnated surface layers 18 to the inner unimpregnated core portion 19, and that although a plurality of recesses is formed which may serve to secure the impregnated layers 18 together, only those recesses need be utilized for nailing to suitably secure the units in their erected position.

In addition to forming an improved nailing construction for these units, it was a principal object of the invention to fabricate the units with a novel means for providing drainage of any condensate or moisture which may form between the contiguous faces of the siding units and the surface to which they are applied and also to provide for some and particularly a slow circulation of air between these faces to decrease any tendency of the formation of condensate and retention of moisture therebetween. Figures 1 to 9 inclusive, illustrate the preferred form of kerfing and modifications thereof for the backs of these prefabricated siding units to attain the principal object of this invention.

A preferred form of kerfing is that illustrated in Figure 2 for the unit 15. Kerfs 26 are formed as indicated and shall be of such a depth and width as to allow for the drainage of any moisture and will, however, not be so small in size that they will form capillary tubes. The kerfs 26 are preferably spaced substantially 4" apart and extend transversely across the unit substantially on a diagonal line as illustrated. The units are beveled about the inner edges thereof, as at 27, to form grooves 28 between contiguous edges of abutting units, thus forming complete drainage and circulatory passages. The kerfs 26 are so formed and spaced that when the units are applied over clapboard siding 27 as illustrated in Figure 3, drainage passages are provided between the pockets 29 formed between the outer face of the clapboard siding and the inner face of the surfacing unit 15.

It is in these pockets 29 that condensate or moisture tends to form which passes through the walls of the building from the interior thereof to the outside and because of the insulating charac-

ter and vapor-sealed construction of the material, tends to collect in these pockets, as well as any moisture which seeps in because of faulty caulked joints, or the like and which because of these pockets, forms pools. In cold climates, this water may freeze solid. The ice in forming expands and tends to exert pressure against the back face of the material which may result in tearing the material and because of the fibrous nature of the siding units, forcing the material over the nail heads, breaking the seal of the material and allowing additional moisture to seep into the porous interior of the material. Moisture which seeps into the interior of the material may cause delamination of the material and further destruction of the unit. By embodying the novel features of this invention in the siding panels, i. e., the improved nailing construction and kerfing to allow for drainage, the destruction of the units as has been previously formed is overcome.

The riveting action of the improved nailing construction prevents the delamination of the impregnated surfaces of the material from the core portion and also prevents seepage of moisture into the interior of the material and further strengthens the material so that the nail heads will not be pulled through the material. In Figure 2 which illustrates the preferred form of back kerfing, the lines 30 indicate the intersection of the lower edge of the clap-board siding with the back face of the siding unit and it is therefore obvious that any pattern of kerfs 26 should serve to provide drainage passages from each pocket to each successively lower pocket formed by successive clapboard sidings.

Other modifications of the kerfing are illustrated respectively in units 31, 32, and 33. In the unit 31, the preferred pattern of kerfs 26 may be connected at their bottom ends by a diagonal continuous passage 34. It is obvious that with this diagonal passage that positive drainage may be had across the back face of the unit due to the interconnection of the pockets 29 formed between the back face of the unit and the face of the clapboard siding. The diagonal passages 34 shall be of such length that at all times irrespective of the exposure of the clapboard siding construction, drainage will be had from one pocket to another downward across the face of the building to the outside.

Similarly, the unit 32 also illustrates a modified pattern of kerfing wherein the panel is formed by similarly formed kerfs placed diagonally with respect to the length of the unit and each of the kerfs 35 spaced longitudinally along the back face of the unit as shown. This pattern of kerfing also provides suitable drainage between the pockets which may be formed between clapboard siding and the siding units.

The unit 33 illustrates a pattern of kerfs 36 which is formed by kerfing the unit transversely across the back face thereof and longitudinally spacing the kerfs 36 as illustrated. This pattern is preferred for the kerfing of the backs of the soldier courses 16 as illustrated in Figure 1 to provide drainage from the bottom grooves 28 to the atmosphere of any moisture which may form in back of the siding and between the surface to which the siding units are applied, and also to allow a slight circulation of air between the contiguous faces thereof through the continuous interconnecting passages or grooves 28 formed by abutting contiguous siding units.

Figure 7 is a vertical section of a unit and

illustrates the preferred depth to which the kerfs extend with respect to the thickness of the unit. The units are preferably fabricated from material $\frac{5}{8}$ " in thickness which is a suitable thickness for renovating buildings without necessitating too much change in the trim of the building. Obviously, units may be fabricated in other thicknesses without departing from the scope of this invention and such an increase in thickness is desired where the prefabricated units are used in lieu of both sheathing and siding, the unit performing the function of sheathing, sheathing paper and siding, as well as a facing material.

Figures 8 and 9 illustrate a modified form of brick siding units wherein thin furring strips 37 are affixed to the back face of the unit by laminating similar materials or by forming the laminations integrally with the siding unit or by nailing or stapling material such as wood strips to the back face of the siding unit. The furring strips 37 are preferably applied in the same patterns as they have been illustrated in Figure 2, wherein the units are shown formed with kerfs on the back face. It is preferred both in forming the siding units with grooves or with furring strips thereon that the grooves and furring strips shall be formed on the material of which the unit is fabricated prior to the surface impregnation thereof to provide a waterproof and vapor-proof sheath for the insulating unit. As illustrated in Figures 6 and 7, the impregnation of the unit should thoroughly saturate the material about the kerfs 26 and similarly the impregnation would take place across the surface of the material in the modified form of unit designated as 38 of Figures 8 and 9. The function of the furring strips 37 is to sufficiently space the rear faces of units 38 from the surface to which they are applied so that the air spaces between these surfaces are interconnected and completely drained of any moisture and condensate which may form therebetween. In the construction illustrated in Figures 8 and 9, the inner edges of the unit may or may not be chamfered, as at 21, to form grooves 28 when contiguous units are abutted together in the erection thereof.

Referring to Figure 1, the application and erection of the units on a face of a building will be described. It is preferred, particularly in renovating the surface of a building, as for instance a clapboard type of home as illustrated in section in Figure 3, that the drip cap of the building about the bottom thereof shall be first removed and, if required, the building furred out from the sills so that the soldier course 16 may be applied in such a manner that the face thereof will be in co-planar relationship with the face of the siding units 15 when they are applied and secured over and to the siding as illustrated in Figure 3. The ship-lap joint construction 39 of the units permits the units to be abutted together in such a manner that a continuous pattern is formed with the mortar lines as indicated at 22 forming a predetermined pattern to simulate brick or other similar construction.

As the units are erected in place, drainage passages 28 are formed by the bevels 21 on the inner edges of the units as illustrated in Figure 2. Thus a complete interconnecting system of passages is formed on the back face of the erected siding units in such a manner that a circulation of air may be had through the grooves 36 of the soldier courses to the grooves 28 and

the interconnecting system of passages formed thereby. The additional passages formed by the kerfs 26 provide additional and definitely interconnecting passages from one pocket 29 to another which are formed between the faces of clapboard siding and surfacing units. Obviously, with this construction any moisture or condensate forming will be drained from one pocket to another down the face of the wall to the outside of the building, therefore preventing in cold weather any formation of ice, which in turn would tend to force the units from their position or to cause the nail heads to penetrate into the material breaking the vapor-seal, consequently allowing moisture to penetrate to the interior of the units.

In the same manner the construction of the siding unit illustrated in Figures 8 and 9 allows for the drainage of moisture and circulation of air between the siding units and the surface to which they are applied. Figure 3 illustrates the usual form of clapboard siding construction through a wall thereof, illustrating the plaster and lath construction 40 applied on the inside of the building to studs 41 and the exterior face of the building formed by a sheathing construction 42 which may be the usual wood sheathing or gypsum board sheathing, or the like construction, over which may be applied sheathing paper 43 providing an air and vapor-seal. Over this sheathing construction, the usual clapboard siding 27 is applied; and, particularly for renovating or changing the appearance of a building embodying such construction, the siding units 15 are applied, which because of their ornamental appearance and simulated masonry construction, cause an ordinary wood frame dwelling to have the appearance of brick construction with the added advantage of the insulation due to the material from which the simulated masonry units are formed. These units 15, when applied on the surface of a building, have the joints suitably caulked and there may be formed, as at 48, wire cut faces on the simulated masonry construction which serve to conceal the vertical joints of the unit, thus making the assembled face of the wall appear as an integrally formed masonry construction.

Figure 4 illustrates the siding units 15 applied over a sheathing paper 43 and sheathing construction 42, and particularly they are useful in the forming of new dwellings wherein a dwelling is desired which is not only insulated, but has the appearance of a masonry, brick, or like surface construction. Figure 5 illustrates a similar form of construction, as in Figure 4, over which has been applied a modified form of brick masonry simulating unit 38, which is formed as described with reference to Figures 8 and 9. In this form of siding unit, the unit is spaced from the surface of the building to which it is applied by a furring strip construction 31 providing interconnecting passages to allow for the circulation of air and the drainage of any moisture which may form between the back face of the unit and the surface to which it is applied.

Referring to Figures 1, 11, and 12, a preferred form of construction will be described which serves to thoroughly secure the vertical joints formed by the contiguous units at the ship-lap joint constructions thereof, so that the edges will not warp or pull away from one another allowing moisture to penetrate the joint construction to the inner face of the unit. This construction for thoroughly affixing the joints is formed by

slotting, as at 44, to receive a transverse member 45 of a clip construction 46. It is preferred in forming the slot 44 that it shall be formed in the material from which the unit is fabricated before it has been impregnated so that after the material has been impregnated, as illustrated in Figure 11, the vertical edge in which the slot is formed is strengthened and rigidified by the impregnation of asphalt or other impregnant. The clip 46 is preferably affixed to the sheathing 27, preferably a clapboard form of construction, so that the transverse portion 45 secures the ship-lap joint to prevent curling or warping outwardly. The next unit is then applied so that the slot or kerf 44 shall slide over the transverse portion 45 of the clip 46.

Referring to Figure 1, the clip 46, as illustrated, is applied to the siding unit 15 and affixed to the sheathing 27. As will be seen at the left hand side of the unit, the nail recesses 23 are at a substantial distance from the joint between contiguous units. Obviously, then, the transverse portion 45 prevents the unit from warping outwardly because of the slot construction 44 having mounted therein the transverse member 45 of the clip. To further secure the joint, staples 47 may be secured through the ship-laps of the contiguous units as illustrated in the enlarged sectional view, Figure 11. Since the units 15 are impregnated at the edges thereof, as at 17, to strengthen and rigidify the joint construction, the staples when they are driven through the material at the joint, are frictionally affixed to the material because of the additional holding power of the material from which the unit is fabricated because of the impregnation thereof. It is also preferred to slot the siding units, as at 48, to allow the staple to be driven below the surface of the depressions 22 forming the mortar simulated joints. As these slots or kerfs 48 are preferably formed before the material has the coating 20 applied thereto, the coating 20 at least partially fills this slot 48 and forms a self-seal for the staples 47 as they are driven in place, thus covering the staple when secured.

In the same manner, the coating 20, as it is applied after the nailing recesses or sections 23 have been formed in the material as described with reference to the coating 20 filling the slots 48, will fill or tend to fill the recesses 23 and forms a self-sealing construction for the nails as they are driven in place to affix the unit. In addition to the seal formed by the coating 20, the impregnation of the intermediate portion 24 of the nailing construction tends to cause self-sealing as a nail is driven through the material at this point. Obviously, therefore, there has been provided at the nailing sections 24, and as at the joints where the units are stapled, a novel form of construction wherein, as securing means are driven through the coating on the material and the impregnated portion of the material, the securing means become self-sealed because of the nature of the impregnation and the coating applied, and the construction at these points, with the impregnated portion tending to grip the nails and staples. Also, as the coating 20 is ordinarily applied hot, there is a tendency for the surface of the coating at 24 and 48 to be slightly depressed indicating attaching points.

The surfacing of the siding units, although it has been particularly described with reference to a coating applied over the surface of the unit in which granules or grits are embedded to form a masonry simulated construction, it is obvious that

the coating may be utilized to embed therein prefabricated thin slabs of material for providing a masonry veneered construction. With the veneer facing, obviously the weight of the unit is increased, and therefore the novel nail construction described is very important for preventing the failure between the nail and the material forming the unit with subsequent and consequent penetration of moisture into the material forming the unit.

It is preferred, however, to fabricate the units as described and particularly to saturate and impregnate the material with a saturating agent as asphalt having a comparatively high melting point of around 140° F. M. P. and substantially free from volatile solvents, with the coating 20 of the material formed from a like material. With this type of impregnation and coating, any possibility of chemical action between the coating and the saturant for the material, such as a permeation of the coating by solvents which dilute the body thereof or impair the adhesive qualities of the coating is avoided.

Although the material is preferably formed by applying the coating in such a manner that the nail receiving recesses 23 are thoroughly filled, however, the nature of the impregnation of the intermediate portion 24 is such that the material at this point and the nail are thoroughly sealed and affixed together because of the frictional increase due to the nature of the impregnation at this point. Therefore, rust proof nails having their heads the same color as that of the coating may be used without any additional painting to improve the appearance. With this construction of the nail receiving sections, as described above, the nail is so sealed that protection of the board by further coating at this point is unnecessary, and all that is necessary to be considered is the color problem for the concealment of the nail. However, as this coating is knife coated or otherwise applied to the material and the depressions 23 being substantially filled serve to indicate where to nail, it is no problem to drive the nail through this filling and thus completely cover up the head of the securing nail so that it may not be noticed from the face of the unit. Depending upon the type of securing means used, it may or may not be necessary to additionally point up the unit where it is secured. If a large headed nail is used the filling at the recess may need further pointing to secure the finished appearance of mortar construction.

It is obvious from the above description that there has been disclosed a novel building member which is so formed as to satisfactorily drain any moisture which may be formed between the unit and the surface siding or sheathing to which it is applied. Furthermore, several patterns have been disclosed for accomplishing this result, and these patterns have been merely illustrative of the range of equivalents which may be used, particularly with respect both to the patterns of the grooves, whether grooves or integral furring strips shall be used and to the respective patterns of the furring strips or grooves.

Also, there has been disclosed a suitable siding unit or construction member which may be readily prefabricated and erected in place to any surface of a wall or building construction for the simulation of a masonry construction. This form of construction has been particularly illustrated with respect to application over clapboard siding and other forms of siding or sheathing

constructions, whether for renovating old buildings or for surfacing the walls of new construction.

In addition, there has been disclosed a novel siding unit or surfacing material having an improved form of nailing constructions wherein the nailing constructions thoroughly seal the material and also act as a self-seal for nails or other securing means applied therethrough. In 10 addition to this, there has been disclosed a novel clip construction and joint construction to prevent the opening up at the joints formed by the surfacing units and to prevent warpage of the material forming the units at the joints thereof from a coplanar surface which would detract from the surface appearance of the assembled units.

It will, of course, be understood that various combinations of the features of the invention, other than the combinations illustrated and described will be obvious to those skilled in the art and are therefore entirely within the scope of the invention as defined by the appended claims. The same applies to various modifications and minor departures from the specific form of prefabricated siding unit as well as the method and means of securing the prefabricated siding units in a wall construction herein illustrated and described in this novel wall surfacing unit and wall construction.

What is claimed is:

1. In a wall structure in combination with an outside surface thereof, facing units applied thereto, such facing units on their rear faces beveled along their vertically directed edges whereby passages are formed between the rear faces of the facing units and the surface of the wall structure, additional recesses in the rear faces of the facing units and providing communication between the aforesaid passageways and providing for the drainage of moisture from and for a slight circulation of air between the rear faces of the facing units and the surface of the wall structure.
2. In a wall structure in combination with an outside surface thereof facing units applied thereto, such facing units on their rear faces beveled along their edge whereby passageways are formed between the rear faces of the facing unit and the surface of the wall structure, additional recesses in the rear faces of the facing units and interconnecting the said passageways formed due to the bevels on the edges of the units and thereby providing interconnecting communications between the aforesaid passageways and providing for the drainage of moisture and for circulation of air between the rear faces of the facing units and the surface of the wall structure.
3. A building unit comprising a fiber board to be secured to a building wall as a facing, weatherproofing material applied to the outer exposed surface of the board and patterned to simulate masonry construction, the opposite rearwardly directed face of the board coated with asphalt and having formed therein interspersed series of interconnecting, inclined and parallel grooves providing when a plurality of the units are secured to a building wall a communicating net work of channels between the rear face of the units and the surface of the building wall and affording drainage throughout the area.
